(57) **CLAIM**

I claim the ornamental design for a TFT LCD television and monitor, as shown and described.

DESCRIPTION

FIG. 1 is a front elevational view of the TFT LCD television and monitor showing my new design;

FIG. 2 is a left angle-side elevational view thereof;

FIG. 3 is a right angle-side elevational view thereof;

FIG. 4 is a top right angle-side elevational view thereof;

FIG. 5 is a bottom right angle-side elevational view thereof;

FIG. 6 is a back elevational view thereof;

FIG. 7 is a top left angle back elevational view thereof; and,

FIG. 8 is a bottom left angle back elevational view thereof.
